MAGNETIC UNIT

Herbert R. Warnke, New York, N. Y., assignor
to Control Instrument Company, Inc., Brooklyn, N. Y., a corporation of New York

Application March 4, 1936, Serial No. 67,025

1 Claim. (Cl. 179—117)

The present invention comprises a magnetic unit or element. This element is especially adapted for sound apparatus such as microphones or loud speakers.

5 The present invention relates to a very powerful permanent magnet element adapted to cooperate with a movable member arranged in a narrow air gap between the terminal poles of the element. This movable member is connected 10 in an electrical circuit in such manner that a movement of the member, as in the case of a microphone, induces an electrical current in the member; or where the member carries a variable electrical current, as in the case of a loud 15 speaker, the reaction between the element and the member produces movement of the member.

The principal feature of the device is a construction wherein the permanent magnets exert a coercive force of a very high number of gibberts; and since the magnetic circuit is capable 20 of a high degree of saturation and its reluctance is low a field of very many gausses is produced in the narrow air gap between the poles.

The permanent magnets used in the device are 25 cast masses of magnetic steel, comprising nickel, cobalt, aluminum, and steel. The permanent magnets are preferably formed of a barrel shaped construction which provides a large central portion adapted to carry magnetic lines of force to a maximum capacity of the mass of metal forming the magnets. The preferred construction of 30 the element comprises a soft iron top plate provided with a circular opening and a similar soft iron base plate carrying a central pole piece also of soft iron. This pole piece extends into the 35 opening in the top plate with a narrow tubular air gap between the upper end of the central pole piece and the top plate. Barrel shaped permanent magnets are mounted between the soft 40 iron top plate and the soft iron base plate and the engaging surfaces between the ends of the barrel shaped magnets and the top and bottom plates are accurately ground plane surfaces to insure of intimate contact between the members.

45 The joint between the central pole piece and the bottom plate is also a ground fit so that the lines of force are transmitted throughout the device without loss at the points of connection. Suitable connecting bolts of brass unite the top plate 50 and the bottom plate to establish compressive forces holding the permanent magnets in position. In order to prevent movement of the magnets on the respective bottom and top plates, small ground dowels extend from shallow openings in the respective plates into similar small

openings provided in the ends of the permanent magnets. The permanent magnets are arranged with similar magnetic poles in contact with the top plate and with opposite magnetic poles in contact with the base plate so that the top plate 5 becomes one magnetic pole and the central pole piece becomes the other magnetic pole.

A suitable carrier for a portion of an electrical circuit is mounted to oscillate in the narrow air gap between the terminal magnetic poles. In the 10 preferred form, this member comprises a voice coil mounted upon a diaphragm. This voice coil is connected with suitable electrical apparatus as is well known in the art. When the diaphragm is vibrated by sound waves, a variable 15 current is established in the voice coil and the device operates as a microphone. Where the voice coil is energized by an electrical current corresponding to a sound wave, the variable current causes the voice coil to oscillate in the air 20 gap and to impart movement to sound amplifying apparatus, which may comprise a cone or other vibrating device utilized for transforming movement into sound waves, as is well known in the art.

25 Other features of the invention will be pointed out hereinafter by reference to the accompanying drawings forming a part of the specification and wherein like parts are indicated by like characters throughout the several figures of the 30 drawings.

It is to be understood that the disclosure here-with is illustrative and is not to be considered in the limiting sense since the invention may be embodied in constructions other than those specifically illustrated and described.

35 Fig. 1 is a plan view of the preferred form of the invention, showing the diaphragm removed.

Fig. 2 is a sectional view on line 2—2 of Fig. 1 showing the diaphragm and voice coil in position and in section.

Fig. 3 is a sectional view on line 3—3 of Fig. 4 also showing the diaphragm and the voice coil in operative position.

Fig. 4 illustrates a modification as to the number 45 of permanent magnet pole pieces of a unit similar to that shown in Fig. 1 with the exception that the number of permanent magnets is increased, that the base plate is round, and that the top plate has been removed.

50 Referring to Figs. 1, 2, and 3, the device comprises a top plate 1, of soft iron, provided with a central opening 2. The top plate 1, in the preferred form of the invention, carries a shouldered brass ring 4 comprising a seat or holder for a 55

suitable diaphragm. This brass ring 4 may be secured to the top plate 1 in any suitable manner as for example by brass machine screws 5. This brass ring has a screw threaded shoulder into which a brass clamp ring 6 is threaded in order to clamp the edges of a diaphragm 7. In the preferred form of the device, the diaphragm 7 is provided with a mounting 8 that carries a voice coil 9 that extends into the opening 2 in the center plate. The top plate 1 is also provided with lugs 10 having mounting openings 11 for mounting the unit in any desired manner. The under surface 12 of the top plate is ground to a plane surface and a plurality of permanent magnets 14 have their ends 15 also ground to plane surfaces in order that an intimate contact may be formed between the permanent magnets 14 and the top plate 1. These permanent magnets 14 are also carefully ground to a common length. The ends of the permanent magnets 14 are recessed to receive dowel pins 16 which set in shallow recesses in the top plate 1. These dowel pins 16 prevent displacement of the permanent magnets 14 on the top plate 1.

25 A bottom plate 17, also of soft iron, is provided with a ground plane surface 18 which contacts with ground surfaces 19 on the ends of the permanent magnets 14. Dowel pins 20 are recessed into the lower ends of the permanent magnets 14 and into the bottom plate 17 to position the permanent magnets 14 relative to the bottom plate 17. This bottom plate 17 carries a soft iron cylindrical pole piece 21, the base of which is ground to a plane surface 22 in order to form an intimate contact with the plane surface 18 on the bottom plate 17. Preferably, the cylindrical pole piece 21 is formed with an integral stub bolt section 24 which is threaded on the portion extending beyond the bottom plate 17 and carries a nut 25.

40 Preferably, the upper end of the cylindrical pole piece 21 has a portion 26 reduced in diameter to extend into the central opening 2 in the top plate and to provide a narrow tubular air gap 27 between the upper end of the cylindrical pole piece 21 and the side walls of the central opening 2. The top plate 1, the bottom plate 17, the central pole piece 21, and the nut 25 are all preferably constructed from soft commercially pure iron in order to form efficient paths for magnetic forces originating with the permanent magnets 14.

45 A brass ring or collar 28 is attached to the under portion of the top plate 1 by suitable screws (not shown) or otherwise, and extends downward to enclose a portion of the cylindrical pole piece 21 in order to accurately center the reduced portion 26 in the central opening 2 of the top plate to provide the uniform air gap 27. Bolts 29, preferably of brass, are secured to the top plate 1, and pass through openings in the bottom plate 17 so that nuts 30 may be utilized to place the bolts 29 under tension to tightly clamp the permanent magnet 14 between the top plate 1 and the bottom plate 17.

55 The construction illustrated in Fig. 4 is similar to the construction illustrated in Figs. 1 and 2 with the exception that the four permanent magnets 14 illustrated in Figs. 1 and 2 are replaced by six permanent magnets 14 in the modified construction. The base plate 31 is circular in form instead of substantially rectangular as illustrated in Figs. 1, 2, and 3. The number of bolts 29 have been increased from four to

six, otherwise the modified construction is substantially the same as the construction illustrated in Figs. 1, 2 and 3.

60 The permanent magnet members 14 are cast masses of special alloy, particularly adapted to constitute permanent magnets having a very high coercive force and preferably comprise an alloy of nickel 8 to 15%, cobalt 2 to 5%, aluminum 10 to 20%, and the remainder steel.

65 The construction is such that after the parts have been all assembled, suitable electrical conductors may be positioned around the permanent magnet members so that an electrical current of very high magnetizing force may be applied to the conductors to permanently magnetize the magnets after the device has been completely assembled with the same magnetic poles of the several magnets all pointing in the same direction. This results in a construction which is substantially permanent in its magnetic characteristics and produces a construction wherein the gauss and gilbert units are very high. The construction is such that the magnetic forces are concentrated in substantially parallel planes extending radially through the air gap 27 so that a concentrated field exists in the air gap. The lines of force in this field are cut by any movement of an electrical conductor vibrating in the field. Since the lines of force through the air gap originate from permanent magnets, the output of the device is free from distortion due to variations in the magnetic field, and, therefore, extremely high fidelity of operation is obtained by the present construction.

70 The usual connections to the voice coil, or vibrating electrical conductor, have been omitted for the sake of clarity. Neither has any amplifying apparatus been shown or described. It is to be understood that all electrical connections are to be made in accordance with the skill of the art and that the device herewith disclosed is to be used in electrical circuits well known to those skilled in the art.

What I claim is:

75 As an article of manufacture, a magnetic unit comprising spaced parallel plates of soft iron; a cylindrical core of soft iron attached to the center of one of said plates and making a machine fit therewith, said cylindrical core extending through an opening located in the center of the other plate and forming an air gap with respect thereto; a plurality of permanent bar magnets of greater cross-section in the middle portion than at the ends thereof and arranged symmetrically around and having the axes thereof parallel to the axis of said cylindrical core, said permanent bar magnets being of barrel shape and comprising supporting struts extending between said plates, the inner sides of said plates being ground to substantial plane surfaces and the ends of said permanent barrel shaped magnets being also ground to substantially plane surfaces whereby the ends of said magnets and the inner sides of said plates form ground fitted engagements to obtain intimate contact between the ends of said magnets and said plates; dowel pins extending into the centers of the ends of said permanent magnets and into said plates to locate said magnets on said plates; and adjustable nonmagnetic tension members comprising screw bolts extending between said plates to urge said plates toward each other and thereby clamp the magnets tightly between the plates.

HERBERT R. WARNE.
